FACELESS DOLL

Murray Goozner, 642 Diane Place,
North Woodmere, N.Y. 11598

Filed June 23, 1972, Ser. No. 265,830

Term of patent 14 years

Int. Cl. D21—01

U.S. Cl. D34—4 R

FIG. 1

FIG. 2

FIG. 3

FIG. 4

FIG. 5

FIG. 1 is a front elevational view of a faceless doll showing my new design;

FIG. 2 is a rear elevational view thereof;

FIG. 3 is a top plan view thereof;

FIG. 4 is a side elevational view thereof; and

FIG. 5 is a bottom plan view thereof.

I claim:

The ornamental design for a faceless doll, substantially as shown.
